United States Patent Office

Des. 203,526

Patented Jan. 18, 1966

203,526

OFFICE FILE TRAY

June A. Bartlett, San Carlos, Calif., assignor to Mosler
Harbor Metal Products Corporation, Belmont, Calif.

Filed Jan. 21, 1963, Ser. No. 73,254

Term of patent 14 years

(Cl. D74—9)

FIG. 1 is a perspective view of the office file tray of my design showing the top, front and right side thereof; and

FIG. 2 is a perspective view of the office file tray of my design showing the bottom, rear and left side thereof.

I claim:

The ornamental design for an office file tray, as shown.
